UNITED STATES PATENT OFFICE.

ALFRED COPONY, OF CHICAGO, ILLINOIS, ASSIGNOR TO WILLIAM H. MINER, OF CHICAGO, ILLINOIS.

SINGLE-CENTER-SILL DRAFT-RIGGING.

1,137,950.

Specification of Letters Patent.

Patented May 4, 1915.

Application filed January 12, 1914. Serial No. 811,622.

To all whom it may concern:

Be it known that I, ALFRED COPONY, a subject of the Emperor of Austria-Hungary, residing in Chicago, in the county of Cook and State of Illinois, have invented a new and useful Improvement in Single-Center-Sill Draft-Rigging, of which the following is a specification.

This invention relates to improvements in single center sill draft rigging.

An object of the invention is to provide a draft gear and single center sill construction having means for automatically maintaining the draft gear in proper position relatively to the sill.

In the drawing forming a part of this specification, Figure 1 is a side elevation of a construction embodying my improvements, Fig. 2 is a horizontal section one-half of which is taken on the line 2-2 of Fig. 1 and the other half of which is taken on the line 2^a-2^a of Fig. 1, and Fig. 3 is a transverse vertical section taken on the line 3-3 of Fig. 1.

The invention consists in the improvements in the parts and devices and in the novel combinations of the parts and devices herein shown, described and claimed.

In said drawing, A designates a center sill of I form having upper flanges 10, web 11 and lower flanges 12, the web being bifurcated at its end as shown at 13. At the rear of the bifurcation, the web of the sill is recessed as at 15 to receive the transversely extending rear follower 16, the front follower 16 being movable within the bifurcation 13. Secured to the center sill on opposite sides thereof are cast steel cheek plates 17 which encircle the recesses in the sill provided for the followers, said castings having front stops 18 and rear stops 19. The cheek plates are also provided at their front ends with abutments or stops 20 against which the rear or inner end of the draw-bar 21 is adapted to strike at the end of the inward movement of the latter, said draw-bar being mounted within the bifurcation 13 as shown. The center sill at its end has riveted thereto a carry iron 22 recessed as at 23 to receive the draw-bar shank therethrough and to provide clearance for the latter. Each cheek plate, near the center thereof, is provided with a laterally and upwardly extending spring supporting arm 24, see Fig. 3.

On each side of the center sill is a yoke arm or link 25 having an elongated recess 26 therein in which the ends of the followers are seated in the manner hereinafter described. The yoke arms or links, at their forward ends, are extended inwardly as indicated at 25^a and are secured to the draw-bar by means of bolts 27 and a key 28. The key 28 extends from the outside face of one end portion 25^a to the outside face of the other end portion 25^a and is curved along its longitudinal edges to fit the bolts 27-27. The extreme edges of key 28 are indicated by the dotted lines 128-128 in Fig. 2, which dotted lines appear approximately centrally 70 of the bolts 27. As will be understood, springs are mounted between the followers on opposite sides of the center sill and supported by the arms 24, said springs being shown in Fig. 3 of the drawing. Each 75 cheek plate is provided with a rearwardly extending slotted extension 29, the center sill being also slotted to correspond therewith and through said slots extends and is slidable therein a bolt 30, the bolt also at its 80 ends being connected to the rear ends 31 of the yoke arms or links 25. Mounted on the bolt 30 on each side of the center sill is a spring 32 which, at its ends, engages rocker washers 33, 33. A thimble 34 is placed between the inner end of the draw-bar and the front follower so that shocks are transmitted directly from the draw-bar to the follower at the center thereof, said thimble being slidable within the bifurcation 13 and 85 between the cheek plates 17.

Referring now more particularly to Fig. 2, it will be seen that the yoke arms 25 are rabbeted or notched as shown at 35 to receive the flanged ends 36 of the followers. 90 With this arrangement, the followers and yoke arms move together when either of them is moved sidewise so that as the yoke arms are automatically centered by the springs 32 on the rod 30, the followers and 95 springs therebetween will also be properly centered. In this connection it will also be noted that the yoke arms pivot or swing about the corners 37 of the cheek plates.

Although I have herein shown and described what I now consider the preferred embodiment of my improvements, yet it will be understood that various changes and modifications may be made without departing from the spirit of the invention, and 100 105 110

all such changes and modifications are contemplated as come within the scope of the claims appended hereto.

I claim:

5. 1. In a car, in combination with a single center sill recessed to receive followers therethrough, of a draw bar, followers extending transversely through said center sill, parallelly arranged springs between said followers, one spring on each side of the center sill, connections between the followers and the draw bar, and spring means located to the rear of the rear follower for maintaining said connections and followers in proper position relatively to the center sill.
- 10 2. In a car, the combination with a center sill recessed to receive followers therethrough, of a draw-bar, followers extending transversely through the center sill, shock 20 absorbing means between the followers, yoke arms connecting the followers and the draw-bar, and transversely arranged springs between the yoke arms and the center sill on opposite sides of the latter for maintaining 25 the yoke arms in proper position relatively to the sill, substantially as specified.
- 30 3. In a car, the combination with a single center sill recessed to receive followers therethrough, of a draw bar, followers extending transversely through said center sill, shock absorbing means between said followers, yoke arms operatively connecting the followers with the draw bar, and means for preventing relative laterally movements between the followers and said yoke arms, said means comprising coöperating flanges and notches to receive said flanges formed on the followers and yoke arms.
- 40 4. In a car, the combination with a single center sill bifurcated at its ends and recessed to receive followers therethrough, of a draw-bar mounted within the bifurcation, followers extending transversely through the center sill, springs between said followers, means operatively connecting the fol-
- 45

lowers with the draw-bar, cheek plates secured to the opposite sides of the center sill and provided with stops for the followers, and spring-supporting arms on opposite sides of the center sill, said spring supporting arms being formed integral with said cheek plates and arranged to directly engage and support said springs, substantially as specified.

5. In a car, the combination with a single center sill bifurcated at its ends and recessed to receive followers therethrough, of a draw-bar mounted within the bifurcation, followers extending transversely through the center sill, each follower being provided with flanged ends, yoke arms encircling the followers and notched to receive said flanged ends, the arms being keyed to the draw-bar, and means for automatically centering the yoke arms and followers relatively to the center sill, substantially as specified.

6. In a car, the combination with a single center sill bifurcated at its ends and recessed to receive followers therethrough, of a draw-bar mounted within the bifurcation, followers extending transversely through the center sill, each follower being provided with flanged ends, yoke arms encircling the followers and notched to receive said flanged ends, the arms being keyed to the draw-bar, and means for automatically centering the yoke arms and followers relatively to the center sill, said means including a bolt extending through the rear ends of the yoke arms and the center sill and slidably mounted in the latter and springs on the bolt between the yoke arms and the center sill, substantially as specified.

Signed this 8th day of January, 1914, in the presence of two witnesses.

ALFRED COPONY.
